[57] CLAIM

The ornamental design for a verge capping member, as shown and described.

DESCRIPTION

FIG. 1 is an end elevation of a verge capping member embodying my new design;

FIG. 2 is a perspective view of the system shown in FIG. 1;

FIG. 3 is a front elevation of the system as shown in FIG. 1; and

FIG. 4 is a bottom plan view of the system as shown in FIG. 1.

The article shown is of indefinite length and of constant crosssection throughout.

FIG. 1

FIG. 2

FIG. 3

FIG. 4
